UNITED STATES PATENT OFFICE.

HARRY R. MASON, OF CHICAGO, ILLINOIS, ASSIGNOR TO THE WESTINGHOUSE AIR BRAKE COMPANY, OF PITTSBURG, PENNSYLVANIA, A CORPORATION OF PENNSYLVANIA.

FLUID-PRESSURE MECHANISM.

SPECIFICATION forming part of Letters Patent No. 718,493, dated January 13, 1903

Application filed May 8, 1901. Serial No. 59,244. (No model.)

To all whom it may concern:

Be it known that I, HARRY R. MASON, a citizen of the United States of America, residing at Chicago, in the county of Cook and State of Illinois, have invented certain new and useful Improvements in Fluid-Pressure Mechanism, (Case No. 3,) of which the following, taken in connection with accompanying drawing, is a specification.

10 This invention has relation to a construction of fluid-pressure mechanism of improved form in which the fluid-pressure is arranged to actuate a controlling device by means of coöperating parts of novel construction so devised that the said controlling device can be brought into operation at any one of a plurality of pressures at will by the manipulation of a suitable manually-operated mechanism.

20 One object of my invention is the provision of a movable abutment for actuating a fluid-pressure valve, said movable abutment being held against fluid-pressure by what I will for convenience of reference hereinafter refer to 25 as a "normal-load device"—that is, a spring or its equivalent—and also under certain conditions or at certain times by a supplemental or auxiliary load device arranged to be brought into operation by a manually-controlled cock or equivalent means.

The above, as well as such other objects as may hereinafter appear, I attain by means of a construction which I have illustrated in preferred form in the accompanying drawing, 35 in which 1 is a valve-casing having an inlet-opening for 2 fluid-pressure and an outlet-opening 3, communication between which is established by a port 4, controlled by a controlling-valve 5, held by a spring 6 and tubular bolt 7 within the stem 8, which, in conjunction with the diaphragm 9, held between the head of the bolt 7 and the stem 8, constitutes a movable abutment for the valve 5. The diaphragm 9 is secured at its outer edge, 40 as at 10, with a ring 11, back of which, held in place by a spring-case 12, is a spring 13, which forms the normal-load device of the mechanism, the tension of the spring or the amount of normal load being determined by

proper adjustment of the adjusting-nut 14, 50 the spring bearing upon a shoulder formed on the stem 8, so as to resist upward movement of the diaphragm or movable abutment from the pressure beneath the same produced by the fluid-pressure coming through the inlet 2.

Pivoted at 15 within the casing 1 is a bell-crank lever 16, one end of which at 17 engages the bolt 7 and the other end of which, 18, has engagement with the sliding plunger 19, but reciprocates within a cylindrical chamber 20 in the plunger-casing 21, the outer end whereof is provided with a three-way cock 22, controlling a passage 23, an outlet to the atmosphere 24, and a passage 25, 65 leading to the rear end of the chamber which contains the plunger 19.

The mechanism described just above constitutes a supplemental-load device for the movable abutment and valve arranged to be 70 thrown into or out of operation at will by suitable manipulation of the cock 22, as will now appear in connection with the operation of my invention, which is as follows: The parts being in the position shown, air entering at 2 75 fills the chamber surrounding the valve 5, the valve 5 being held shut until pressure accumulates beneath the movable abutment 9 sufficient to overcome the resistance of the normal load of the spring 13, determined by 80 the adjustment of the nut 14, when the valve 5 will be raised and fluid-pressure permitted to escape through the outlet-passage 3. In this position of the parts the supplemental-load device adds nothing to the normal load, 85 because the pressures on the opposite sides of the plunger 19 are balanced through the passages 23 and 25, which are in communication through the cock 22. If, however, it be desired to increase the load upon the diaphragm 90 or movable abutment, the cock 22 is turned so as to establish communication between the passage 25 and the opening 24, leading to the atmosphere, whereupon the balance of the pressure at the right of the plunger 19 being 95 removed the entire area of the said plunger then becomes effective to exert a force tending to pull downward upon the valve 5. This

force thus being added to the normal load or force of the spring 13 requires a higher pressure to cause the unseating of the valve. Thus any desired difference in pressure may be produced by a variation in the size of the plunger 19 or the leverage through which the force thereof is communicated to the movable abutment. If it is desired to employ this device in conjunction with a plurality of different pressures, two or more than two plungers 19 might be added, with suitable ports and passages for controlling their operation in a manner substantially the same as is shown in the accompanying drawing.

Having thus described my invention, what I claim as new, and desire to secure by Letters Patent, is—

1. A fluid-pressure mechanism, comprising a casing, a valve, a movable abutment exposed on one side to fluid-pressure for opening said valve, an adjustable spring opposing said fluid-pressure, a plunger having equal areas on its opposite sides exposed to fluid-pressure, connections between the plunger and said valve, and a cock for releasing the pressure from one side of said plunger.

2. A fluid-pressure mechanism, comprising

a casing, a valve, a movable abutment exposed on one side to fluid-pressure for actuating said valve, an adjustable spring opposing the movement of said abutment, a plunger normally exposed on its opposite sides to fluid-pressure, a bell-crank connection between the plunger and said valve, and a cock for releasing the pressure from one side of said abutment.

3. A fluid-pressure mechanism, comprising a valve, a movable abutment therefor, a spring for maintaining a normal load upon said movable abutment, an adjusting device for regulating the normal load, and a supplemental-load device comprising a plunger having equal areas subject to fluid-pressure upon its opposite sides, a connection between said plunger and said movable abutment, and a valve for throwing said supplemental plunger into and out of operation, substantially as described.

In testimony whereof I have hereunto set my hand in the presence of two subscribing witnesses.

HARRY R. MASON.
